MILLING MACHINE

Filed Aug. 5, 1927

UNITED STATES PATENT OFFICE

LESTER F. NENNIGER, OF CINCINNATI, OHIO, ASSIGNOR TO THE CINCINNATI MILLING MACHINE COMPANY, OF CINCINNATI, OHIO, A CORPORATION OF OHIO

MILLING MACHINE

Application filed August 5, 1927. Serial No. 210,867.

This invention relates to improvements in milling machines or like machine tools and has particular reference to the frame structure thereof.

- 5 In the operation of milling machines or the like for quantity production considerable difficulty is frequently experienced due to piling up of the removed chips and the making of proper disposition of these so 10 they will not clutter up the floor, interfere with proper loading and removal of the work or operation thereof and at the same time so that the chips permit of their being readily collected.
- 15 Also, the presence of the piled chips on the table tends to cause undue splashing or spreading of the coolant and involves difficulties in the proper leading of the coolant back into the cooling pan on the machine 20 for reutilization.

It is therefore the purpose of the present invention to provide an improved machine tool structure which shall satisfactorily take care of and substantially automatically collect 25 the chips and prevent their being spread over the floor and about the machine.

A further object of the invention is the provision of improved structure which will most satisfactorily care for the coolant and 30 collect the same with minimum of splashing, thus keeping the machine as an entirety and the floor therearound in a more clean, healthy and sanitary condition.

Other objects and advantages of the present invention should be readily apparent by 35 reference to the following specification taken in connection with the accompanying drawings, and it will be understood that I may make any modifications in the specific structural details hereinafter disclosed within the 40 scope of the appended claims, without departing from or exceeding the spirit of the invention.

Figure 1 is a side elevation of a milling 45 machine embodying these improvements.

Figure 2 is a plan view of the front portion 50 of the bed and table, and

Figure 3 is a vertical section as on line 3—3 of Figure 2.

55 In the drawings the numeral 10 designates

the main bed portion of a milling machine having secured thereto the column 11 supporting the spindle 12 for arbor 13 bearing the milling cutter 14.

As will be best understood by reference to 55 Figure 3 the bed 10 in place of being substantially solid is in the form of a hollow shell providing a large interior chamber as at 15 and a second subtending smaller chamber 16. Projecting inwardly of the bed intermediate these chambers is the flange 17 which provides a support for the removable screen member 18. Below the flange 17 the bed is further formed with the interior rib 19 forming a sliding support for the peripheral flange 20 of the coolant pan 21.

As is shown in Figures 2 and 3 the bed is substantially open at the top throughout its length except for the transverse ribs 22 disposed at a plurality of points and serving as 70 bridge truss members both bracing the bed and supporting the longitudinal plate or casting 23, providing the ways 24 for the longitudinally shiftable work supporting table 25. This table 25 it will be noted has at 75 one end the trough portion 26 having a discharge end or return 27 which extends back over the open space 28 of the interior of the bed at its limit of movement as shown in Figure 2, so that coolant and chips from the 80 table will at all times be discharged into said open space.

From the foregoing description the general structural features of the present invention should be readily apparent and it will 85 be noted that there has been provided at the upper part of the bed of the machine, in place of a solid top a skeleton framework or support constituting guideways for the work supporting table having at each side thereof 90 completely open coolant and chip receiving spaces through which both coolant and chips may drop into the interior of the machine and whose entrances are so large as to absolutely prevent any possibility of clogging, 95 interfering with the passage of either the solid or liquid material.

It will further be noted that by this construction the bed itself forms the containing chamber for separation of the solid and 100

liquid matter, in which a large receiving chamber is provided for the chips or solid matter which build up and increase in volume and at the same time a smaller but sufficiently large chamber to receive the return coolant which may consequently be readily reutilized.

In order that all of the chips and the coolant may be properly directed into the interior of the bed, use is preferably made of lateral guide members 29 either integral with the bed or auxiliary members removably secured thereto and extending upward above the top of the table. With such a structure the workman may easily brush the table, all particles carried over to the side, dropping down into the bed and being separated from the coolant by the intermediate screen member 18.

20 To facilitate removal of the chips there is preferably provided in one end of the bed a cleaning aperture 31 while the bed is also formed with a second aperture or guideway 32 through which the coolant pan 21 may be removed when desired.

It will further be noted that by the removable supporting of the screen 18 the chips therefrom may be thus withdrawn through aperture 31 or the screen itself may be taken out through said aperture for suitable cleaning whenever there may be tendency of same to become clogged.

I claim:

1. As an article of manufacture, a milling machine bed casting comprising a hollow shell having enclosing side and end walls, transverse truss ribs integral with and connecting said side walls, a longitudinally extending skeleton frame member integral 35 with and centrally connecting said ribs said member having table engaging ways formed on the upper face thereof, substantially as and for the purpose described, said integral casting having additionally inwardly extending 40 rib or flange portions forming a partial lower closure for the enclosed chamber of the bed casting and adapted to support a member for reception of discharge from the machine table when in use.

50 2. A bed unit for a milling machine or the like comprising a hollow rectangular shell having joined end and side walls providing an interior chamber, a coolant reservoir forming a closure for the bottom of the chamber, a perforated chip receiver superimposed on said reservoir, spaced transverse ribs connected to the side walls at the upper portion thereof to laterally brace the walls and form large chip and coolant passages between the 55 same, a frame member of less width than the bed extending longitudinally thereof and supported by the ribs, guideways formed on said member and a table slidably mounted on said guideways, said table being of substantially the same width as said member whereby

chips and coolant may fall by gravity therefrom directly through said passages to the receivers in the bottom of the bed.

3. A machine tool having a bed comprising integrally connected end and side walls one of the walls having an attachment surface formed thereon, a column mounted adjacent the bed and attached to said surface, spaced ribs integrally connected between the side walls for bracing the same, a frame mounted in the top of the bed and extending transversely of and supported by said ribs in spaced relation to the side walls forming a series of longitudinal openings between each side of the frame and the adjacent side walls, a table reciprocably mounted on said frame, means to divide the interior of said bed into a large and small chamber in superimposed relation to one another, a chip receiver formed in the bottom of the large chamber, and a coolant receiver mounted in the small chamber, whereby chips and coolant will fall directly from the said table through said opening and be collected and separated by said receivers.

4. A machine tool having a bed comprising integrally connected end and side walls, one of said walls having an attachment surface formed thereon, a column mounted adjacent to the bed and attached to said surface, spaced ribs and extending transversely thereof and substantially parallel to but integrally connected between the side walls for bracing the same, a frame mounted in the top of the bed on said ribs in spaced relation to the side walls to form a longitudinal series of openings between each side of the frame and the adjacent side wall, longitudinal guideways formed on the frame, a table reciprocably mounted on said guideways, an internal flange projecting from said walls of said bed dividing the interior thereof into upper and lower chambers, a chip receiver supported by said flange whereby chips will be collected in said upper chamber, an internal rib projecting from the walls of said lower chamber, a coolant reservoir supported on said rib, one of said end walls having an opening therein whereby chips may be removed from the upper chamber during the operation of the machine.

5. A machine tool having a bed comprising integrally connected end and side walls forming a rectangular interior chamber, one of said walls having an attachment surface formed thereon, a column mounted on said bed and attached to said surface, spaced ribs having inclined upper surfaces integrally connected between the side walls for bracing the same, a frame mounted in the top of said bed and extending transversely of and supported by said ribs in spaced relation to the side walls to form a longitudinal series of openings between each side of the frame and the adjacent side wall, longitudinal guide-

ways formed on the frame, a table recipro-
cally mounted on the guideways, a trough
portion formed at the end of the table having
a return overlying the bed to discharge into
5 one of said openings, an internal flange pro-
jecting from the side walls of said bed divid-
ing the interior thereof into upper and lower
chambers, a chip receiver supported by said
flange, whereby chips will be collected in said
10 upper chamber, an internal rib projecting
from the wall of said lower chamber, and a
coolant reservoir supported on one of said
ribs, said end walls having openings whereby
the chips may be removed during operation
15 of the machine.

In testimony whereof I affix my signature.
LESTER F. NENNINGER.
